US00D863347S

(12) **United States Design Patent** (10) **Patent No.:** **US D863,347 S**
(45) **Date of Patent:** **** Oct. 15, 2019**

(54) **DISPLAY SCREEN WITH GRAPHICAL USER INTERFACE**

(71) Applicant: **Aspen Technology, Inc.**, Bedford, MA (US)

(72) Inventors: **Ashok R. Subramanian**, Cambridge, MA (US); **Samuel Provencher**, Waltham, MA (US); **Jack Shapiro**, Nashua, NH (US)

(73) Assignee: **Aspen Technology, Inc.**, Bedford, MA (US)

(**) Term: **15 Years**

(21) Appl. No.: **29/604,945**

(22) Filed: **May 22, 2017**

Related U.S. Application Data

(62) Division of application No. 29/550,221, filed on Dec. 31, 2015, now Pat. No. Des. 790,572, which is a division of application No. 29/482,198, filed on Feb. 14, 2014, now Pat. No. Des. 750,123.
